UNITED STATES PATENT OFFICE

2,112,571

PAPER CONTAINER

Clifford Lancaster Marshall, Newark, N. J., assignor to Mono Service Company, Newark, N. J.

Application August 10, 1936, Serial No. 95,262

1 Claim. (Cl. 229—51)

This invention relates to conical double-walled paper containers such as are described in the specification of prior Patent No. 2,033,724, which are applicable for use in the delivery of milk and the like, and also for marsh-mallow and other semi-liquid or liquid products. In the specification of such prior patent means are described for opening the containers, which comprise a conical double-walled body and suitable end closures, by forming a single weakening line around the outer wall thereof and a cut around the inner wall, these being so disposed that by pressing the side of the body immediately below the weakening line the latter will be broken, and the upper end of the container above the weakening line, together with the closure secured therein, can then be entirely removed by a hinging movement, and if desired be subsequently replaced to serve as a cover.

In the prior patent the weakening line in the outer wall of the container and the cut in the inner wall thereof are both arranged substantially parallel with the upper edge of the container, throughout their whole length, but in practice it has been found that an improved result can be obtained by forming the weakening line with a tab-shaped extension projecting downwardly at a suitable point, and slanting the weakening line slightly downwardly on each side of such tab-shaped extension as hereinafter described and as illustrated in the accompanying drawing. In which Fig. 1 is a plan view of the blank for the body of the container, Fig. 2 a side view of the upper end of a finished container, Fig. 3 a perspective view illustrating the first step to be taken in opening the container, and Fig. 4 a sectional view on an enlarged scale of part of an opened container with the removed top ready to be applied for use as a cover.

As shown in Fig. 1 of the drawing it will be seen that the blank 1 for the body of the container is formed with a weakening line 2 in that part A which forms the outer wall when the body is rolled up, but that instead of being a continuous line as described in the prior Patent No. 2,033,724 it has a tab-shaped portion 3 depending downwardly at a point which is preferably located approximately opposite the lapped joint of the body. This weakening line 2 may be formed as shown in Fig. 1 by a series of short cuts through the material, leaving uncut portions or adhesions 4 serving to hold the parts together. It is preferred to space these uncut portions closer together around the tab-portion 3 and immediately adjacent thereto than elsewhere, as this has the effect

of facilitating the opening operation and strengthening the finished container.

In the prior patent the weakened line 2 was described as being parallel or approximately so with the adjacent edge of the blank 1, but according to the present invention it is preferred to slope it downwardly on each side of the tab-portion 3, as shown clearly in Fig. 1.

The inner end of the weakened line 2 leads upwardly at 5 to a cut 6 formed around the part B of the blank 1 which forms the inner wall of the finished container. This cut 6 is practically continuous, and approximately parallel with the adjacent edge of the blank and nearer such edge than the weakening line, as in the prior patent, 15 but to facilitate the rolling-up operation, particularly when this is effected by automatic machinery, it is preferred, as in the prior patent, to interrupt it at suitable intervals, as 7, which will hold the blank together and prevent the possibility of the part 8 thereof between the cut and the adjacent edge of such blank from interfering with the rolling operation, while at the same time the interruptions 7 can be very easily broken when the container is to be opened.

The blank 1 is intended to be rolled up to form a conical double-walled body, the smaller end of which is shown in Figs. 2, 3, and 4. Into this smaller end a closure such as 9 is inserted in the course of manufacture, the other or larger end 30 being left open until the container has been filled, after which a suitable closure is also to be inserted therein. It is intended that the container shall then be reversed so that the smaller end in which the opening means described are formed becomes 35 the top.

When the container is to be opened this can be readily effected by pressing with the thumb on the tab 10 formed by the tab-shaped extension 3 formed in the weakening line 2, as shown in Fig. 4. This will break the material around such tab 10 as shown, forcing the parts to the position shown in broken lines in Fig. 4, and then by pulling on the upper end of the container at this point, or getting a grip under the broken edge, 45 the entire top with the end closure 9 held therein can be easily removed.

The mechanism employed for applying adhesive to the blank is so arranged that such adhesive shall not be applied to the part thereof which when the body is rolled up is between the weakening line 2 and the cut 6, as the subsequent treatment with paraffin wax or other material will give sufficient adhesion at this point until the con- 55

tainer is opened, but will readily yield when this is done.

As in the prior patent it is preferred, if the removed top is to be used as a cover, that the cut 6 should be formed at such a position in blank 1 that when the container is made up it will be slightly above the under surface of the end closure 8, as shown in Fig. 4, so that a slight groove 11 will be left when the container has been opened 10 into which the remaining upper edge of the container left by cut 6 will enter when the top is replaced, making a good joint. The object of sloping the weakening line 2 downwardly on each side of the tab-shaped portion 10 is to increase 15 the length of the depending portion of the outer wall, while facilitating the opening by reducing such length on each side of the tab-portion.

The making of a good joint when the upper part is used as a cover will be assisted by the small fillet 20 of wax, shown at 12 in Fig. 4, which is usually obtained in carrying out the waxing operation.

When replacing the top the parts which were pressed in to start the opening operation should of course be straightened out again to their normal positions.

What I claim and desire to secure by Letters 5 Patent is:—

In a double-walled conical paper container provided with means for opening same comprising a single weakening line formed with a tab-shaped downwardly extending portion in the outer wall, 10 such weakening line being sloped downwardly on each side of such tab-shaped portion, and connecting at its inner end with a cut extending around the inner wall, and arranged approximately parallel with the adjacent edge of the blank from which the body is made but nearer such edge than the weakening line, as set forth.

CLIFFORD LANCASTER MARSHALL. 20
